(57) **CLAIM**

The ornamental design for a solar string light set as shown and described.

DESCRIPTION

FIG. 1 is a perspective view of a solar panel of a solar string light set showing our new design, shown separately for illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a light string of the solar string light set, shown separately for illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is an enlarged view of portion 17 shown in FIG. 9;

FIG. 18 is an enlarged view of portion 18 shown in FIG. 10; and,

FIG. 19 is a perspective view of the solar string light set. The solar string light set is shown with a symbolic break in the length of the light string and the appearance of any portion of the light string between the break lines form no part of the claimed design. The dash-dash broken lines in the drawings depict portions of the solar string light set that form no part of the claimed design. The dot-dash broken lines represent boundaries of the enlarged portions and form no part of the claimed design.
